INVENTOR:

By Arthur Deichmann
Wm Wallace White
ATTY.

UNITED STATES PATENT OFFICE.

ARTUR DEICHMANN, OF COLOGNE-MARIENBURG, GERMANY.

GOLF-STROKE COUNTER.

1,421,070.

Specification of Letters Patent. Patented June 27, 1922.

Application filed April 16, 1921. Serial No. 462,074.

To all whom it may concern:

Be it known that I, ARTUR DEICHMANN, citizen of Germany, residing at Cologne-Marienburg, Germany, have invented new 5 and useful Improvements in Golf-Stroke Counters (for which I have filed application in Germany July 21, 1919, Patent Number 337,378, April 18, 1921), of which the following is a specification.

10 This invention relates to a golf stroke counter consisting of a plurality of adjustable numbered discs placed side by side. Golf stroke counters of this type hitherto known operating with ratchet wheels and 15 ratchet pawls were complicated in construction and were liable to get out of order easily in consequence of the breaking or bending of a pawl.

In such constructions also the numbered 20 discs could only be turned in one direction.

All these disadvantages are obviated by the invention according to which the various discs are provided on their adjacent sides with interengaging corrugations, corresponding in number to the number of figures 25 on the discs, so that when the discs are turned in either direction they automatically snap into the positions of adjustment.

One form of the invention is illustrated 30 by way of example in the accompanying drawings in which:

Figure 1 is a longitudinal section,

Figure 2 is a cross section and

Figure 3 is an elevation.

35 In the example illustrated the numbered discs *a* are in the form of rings which are rotatably mounted side by side on a tube *b*. The rings are resiliently clamped together by end discs *c* under the action of a tension 40 spring *d* arranged in the tube *b* and connecting the two end discs *c*. The row of numbered discs *a* is completed by a rotatable disc *e*, which is not provided with figures, but simply with a marking stroke *f*.

45 In the example illustrated each disc bears on its periphery the numerals 0 to 9. Each time a player holes a ball he sets the corresponding disc with the numeral agreeing with the number of strokes taken opposite 50 to the stroke mark *f*.

When the player has completed the whole course, the golf counter will indicate, by the row of numbers to the right of the mark

f, successively the number of strokes between the separate holes of the course, so that the 55 result of the play will be seen at a glance.

The spring *d* is of suitable strength to set up sufficient friction between the discs to prevent accidental rotation.

As illustrated in Figure 3 the adjacent 60 sides of the numbered discs may be provided with corrugations *g* of such form that each numbered disc when moved through one digit automatically snaps into its new 65 position and remains therein. This avoids accidental displacement of the discs when the counter is carried in the pocket.

The golf counter illustrated is provided with nine numbered discs *a* but it may be provided with 18. Additional numbered 70 discs *h* may be provided at the side of the marking disc *e* for indicating the total of the separate results indicated by the numbered discs *a*. Any suitable number of these additional discs may be employed. 75

The golf stroke counter according to the invention may be made of any suitable material such as brass, aluminium, ivory and the like. Modifications may be made in the details of the example of construction illustrated, for instance the inner tube could be omitted and the numbered rings could be replaced by solid numbered discs adapted to turn on a central axis, the spring being provided at one end of the counter. 80

Having now particularly described and ascertained the nature of my said invention and in what manner the same is to be performed, I declare that what I claim is:— 85

1. A golf stroke counter comprising a 90 plurality of indicating discs arranged side by side, the faces of the discs having corrugations thereon, and means adapted to cause the discs on rotation in either direction to snap automatically into the positions of 95 adjustment.

2. A golf stroke counter comprising a plurality of indicating discs arranged side by side, the faces of the discs having corrugations thereon, and a spring adapted to 100 cause the discs on rotation in either direction to snap automatically into the positions of adjustment.

3. A golf stroke counter comprising a plurality of discs having numerical indications 105 on the periphery, and corrugated end sur-

faces having a corrugation corresponding to each indication, and means for retaining said discs in a column.

4. A golf stroke counter comprising a plurality of discs having numerical indications on the periphery; and corrugated end surfaces having a corrugation corresponding

to each indication, and resilient means for retaining said discs in a column permitting a relative rotation when desired.

In testimony whereof I have signed my name to this specification. 10

ARTUR DEICHMANN.
